Patented Dec. 21, 1965

203,283

TOY AIRPLANE

James F. Woods, Santa Monica, Calif., assignor, by mesne assignments, to American Machine & Foundry Company, New York, N.Y., a corporation of New Jersey

Filed Oct. 14, 1964, Ser. No. 82,176

Term of patent 7 years

(Cl. D34—15)

FIG. 4.

FIG. 5.

FIG. 6.

FIG. 1 is a perspective view of a toy airplane showing my new design;

FIG. 2 is a right-hand side elevation;

FIG. 3 is a top plan view;

FIG. 4 is a front view;

FIG. 5 is a view from the rear; and

FIG. 6 is a bottom view.

The essential features of my design reside in the portions shown in full lines.

I claim:

The ornamental design for a toy airplane, substantially as shown and described.
